(57) **CLAIM**

The ornamental design for a display screen with transitional graphical user interface, as shown and described.

DESCRIPTION

FIG. 1 is a front view of the first image in a sequence of a display screen with transitional graphical user interface showing our new design according to a first embodiment; FIG. 2 is a front view of the second image thereof; FIG. 3 is a front view of the third image thereof; FIG. 4 is a front view of the fourth image thereof; FIG. 5 is a front view of the first image in a sequence of a display screen with transitional graphical user interface showing our new design according to a second embodiment; FIG. 6 is a front view of the second image thereof; FIG. 7 is a front view of the third image thereof; and, FIG. 8 is a front view of the fourth image thereof. The outer perimeter broken lines in the figures depict a display screen and form no part of the claimed design. The remaining broken lines in the figures depict portions of the transitional graphical user interface and form no part of the claimed design. The subject matter of this patent includes a process or period in which an image sequentially transitions into another image. This process or period forms no part of the claimed design.
